UNITED STATES PATENT OFFICE.

LOUIS G. MILLER, OF FOUNTAIN HILL BOROUGH, PENNSYLVANIA, ASSIGNOR TO
BETHLEHEM STEEL COMPANY.

SIDE FRAME FOR CAR TRUCKS.

Application filed August 27, 1924. Serial No. 734,393.

My invention relates to side frames for car trucks, and has for an object the provision of adequate bearing surfaces between the bolster guide casting and the compression and tension components of the frame, irrespective of variations in said casting.

In the drawing I show in Fig. 1 a side elevation in part section of the side frame; in Fig. 2 an end elevation of same; and in Fig. 3 a section across the line III—III in Fig. 1.

In Figs. 1, 2 and 3, I show a casting 11 of inverted yoke construction, forming a pair of truck columns 12 joined at their lower ends by a longitudinal portion 13, the latter providing a spring seat. The upper ends of the columns 12 are cored out to provide sockets 14, the lower internal faces of said sockets being inclined or tapered.

A similar socket 15 is provided at the center of the longitudinal portion 13, having likewise a lower internal face inclined or tapered. I also show an upper arch bar, or compression member 16 of flat plate construction passing through the sockets 14 and extending forwardly and rearwardly therefrom. These extended portions of the arch bar are deflected slightly downwards and terminate in horizontal bearing plates 18 in the usual manner. A truss bar 19 and a tie bar 20 pass through the lower socket 15. The truss bar 19 extends upwards from the lower socket and is secured by rivets to the bearing plates 18 of the arch bar.

To avoid the necessity of counter-sinking the truss bar for the rivet head, I make the bearing plates 18 and the ends of the truss bar of concavo-convex construction, thereby providing clearances for the rivet heads above the journal boxes. The tie bar 20 is also extended forwardly and rearwardly to the lower portion of the journal boxes. Bolts 21 serve to secure the arch bar, the truss bar and the tie rod to the journal boxes.

In order to provide adequate bearing surface to the compression and tension members, and to compensate for variations in the cored dimensions of the sockets, I insert wedges 22 between the faces of the arch bar 16 and the sockets 14. These wedges have a taper corresponding to the tapered wall of the sockets 14. In the same way a wedge 23 is inserted between the tie bar 20 and

the socket 15. These wedges insure adequate bearing surfaces regardless of any variations in the dimensions of the cored sockets. When the wedges have been driven home, they are held in their respective positions by suitable rivets, said rivets also passing through the corresponding members and sockets.

Having thus described my invention, what I claim as new and desire to secure by Letters Patent is:—

1. In a side frame for a car truck consisting of a bolster guide casting, a compression member and tension members, the combination of sockets in the upper portion of the bolster guide casting for the compression member, a socket in the lower portion of the casting for the tension members, said sockets having their lower internal faces tapered, wedges inserted between the tapered faces of the sockets and the members to substantially support said members, and means securing the wedges when so inserted.

2. In a side frame for a car truck, the combination of two truck columns, a spring seat joining said columns at their lower ends and integral therewith, a compression member passing through said columns, tension members passing through the spring seat, and wedges inserted at the intersection of the compression member with the columns, and at the intersection of the tension members with the spring seat.

3. In a side frame for a car truck, having compression and tension members secured to journal boxes, the combination of an inverted yoke, said yoke providing a spring seat, a bolster guide and sockets for the compression and the tension members, and wedging means for effectively clamping said members to the yoke.

4. In a side frame for a car truck having journal boxes, the combination of a bolster guide casting, a compression member and two tension members, said members extending to journal boxes and having straight end portions adapted to be secured thereto, the end portions of the compression member and of the first tension member having corresponding concavo-convex portions shou-
105
dering on each other, rivets securing these members to each other at their concavo-convex portions, the heads of said rivets

thereby clearing the upper surface of the journal boxes, the end portions of the second tension member extending to the base of the journal boxes, bolts securing all the members to the journal boxes, two upper sockets, a lower socket, said sockets disposed in the bolster guide casting, adjusting means in said sockets to clamp the compression

member to the upper sockets, and the tension members to the lower socket, and rivets to 10 secure said adjusting means in their clamping position.

In testimony whereof I hereunto affix my signature this 25th day of August, 1924.

LOUIS G. MILLER.
